(57) **CLAIM**

The ornamental design for a television receiver, as shown and described.

DESCRIPTION

1. Television receiver

1.1 : Front perspective view

1.2 : Rear perspective view

1.3 : Front view

1.4 : Rear view

1.5 : Left view

1.6 : Right view

1.7 : Top view

1.8 : Bottom view

1.9 : Front perspective view, shown installed on a stand

1.10 : Rear perspective view, shown with stand and cable components

1.11 : Front view, shown with a rotated display panel

1.12 : Right view, shown in a state of use, with the display panel in an alternate position

1.13 : Top view, shown in a state of use, with the display panel in an alternate position

1.14 : Rear perspective view, in a landscape orientation, shown with an extension to the integral stand portion

1.15 : Rear perspective view, in a portrait orientation, shown with an extension to the integral stand portion

The broken lines in reproductions 1.9-1.15 depict environmental matter such as stands and connecting cables which are included for the purpose of demonstrating conditions of use and form no part of the claimed design.

1 Claim, 15 Drawing Sheets
